(57) **CLAIM**

The ornamental design for the railroad attachment clamp, as shown and described.

DESCRIPTION

FIG. 1 is perspective view of the railroad attachment clamp; FIG. 2 is a front view of the open end of the railroad attachment clamp;

FIG. 3 is a rear view of the closed end of the railroad attachment clamp;

FIG. 4, is a right side plan view of the railroad attachment clamp;

FIG. 5, is a right side plan view of the railroad attachment clamp;

FIG. 6 is a top view of the railroad attachment clamp;

FIG. 7, is a bottom plan view of the railroad attachment clamp; and,

FIG. 8 is a top perspective view of the railroad attachment clamp with a track rail as environment.

The portions of the clamp shown in broken lines form no part of the claimed design. The dot-dash lines represent the boundary between claimed and unclaimed portions of the clamp, and form no part of the claimed design. The broken line showing of a track rail depicts environment only and forms no part of the claimed design.
